Attorney, Agent, or Firm—Roger A. Marrs

[57] CLAIM

The ornamental design for lawn sprinkler valve handle, substantially as shown and described.

DESCRIPTION

FIG. 1 is a front elevational view showing my new design for a lawn sprinkler valve handle;

FIG. 2 is a side elevational view thereof;

FIG. 3 is a front elevational view of a modified form of the lawn sprinkler valve handle shown in FIG. 1; and

FIG. 4 is a side elevational view of FIG. 4.

FIG. 1

FIG. 2
